UNITED STATES PATENT OFFICE.

JOHN H. GAVIN, OF CHICAGO, ILLINOIS, ASSIGNOR TO L. WOLFF MANUFACTURING COMPANY, OF CHICAGO, ILLINOIS, A CORPORATION OF ILLINOIS.

COMBINED LAVATORY AND SANITARY DRINKING-CUP.

1,031,843.

Specification of Letters Patent.

Patented July 9, 1912.

Application filed November 28, 1911. Serial No. 662,856.

To all whom it may concern:

Be it known that I, JOHN H. GAVIN, a citizen of the United States, residing in Chicago, in the county of Cook and State 5 of Illinois, have invented a new and useful Improvement in Combined Lavatories and Sanitary Drinking-Cups, of which the following is a specification.

This invention relates to lavatories and 10 more particularly to a sanitary, vitreous, combined drinking cup and lavatory.

The object of my invention is to provide a combined sanitary drinking cup and lavatory preferably integrally formed, of vitreous material which shall be simple and 15 cheap to manufacture, compact and one in which the drinking cup is easily accessible to the user.

Still another object is to provide a structure of the kind described in which the lavatory supply spout is formed or cast integrally with the other portions.

My invention may be used in all places where individual lavatories and sanitary 25 drinking cups are desirable but the structure which I have shown is more especially designed for use in prisons and the structure is so made that there are practically no exposed metallic parts either in the form of 30 faucets or spouts, and all connecting plumbing is concealed when the lavatory is in place.

My invention may be embodied in various forms of lavatories other than the one which I 35 have shown, as will be obvious to those skilled in the art, and it will be understood that the form which I have shown is illustrative only, for the purpose of giving a better understanding of the invention. I have shown 40 my improvements as applied to a flat back, vitreous lavatory but all changes and modifications are contemplated as fairly come within the scope of the appended claims.

My invention furthermore consists in the 45 improvements in the parts and devices and in the combinations of parts and devices herein shown, described and claimed.

In the drawings forming a part of this 50 specification Figure 1 is a side view of a lavatory embodying my improvements, showing the wall to which it is attached, in cross section. Fig. 2 is a front view of the structure disclosed in Fig. 1, the wall having been omitted and the plumbing being shown

in dotted lines. Fig. 3 is a vertical cross section, upon an enlarged scale, of the improved lavatory taken on the line 3-3 of Fig. 2. Fig. 4 is a plan view of the lavatory.

In the drawings, 10 denotes the basin of 60 the lavatory which is formed of vitreous material or any suitable substance and which may be of any suitable or well known shape and is preferably provided with an integrally formed depending flange 11. 65 Also formed preferably integrally with the basin or main portion 10 of the lavatory is a vertical back or wall piece 12 and cast integrally with this back piece 12 and preferably at the central portion thereof is a sanitary, fountain or bubbling, drinking cup 13, said cup 13 being located preferably above the top line of the basin 10 and extending partially thereover and having a recessed or bell shaped mouth. Intermediate the 70 drinking cup 13 and the basin 10 and located preferably directly below the drinking cup is a spout 14 having a supply opening 15 therein for supplying water to the lavatory. The drinking cup 13 is also provided with 75 a supply opening 16 the same being preferably located above the supply opening 15 for the lavatory, and intermediate the supply openings 15 and 16 and preferably communicating with each is a drain 17 for the 80 drinking cup 13 whereby any water that remains in the drinking cup, after the same has been used will be drained into the basin of the lavatory. The lavatory basin is also provided with an overflow recess 18 preferably located in the rear portion thereof beneath the spout 14. The basin is also provided with the usual drain recess 19 which may be of any suitable form and which communicates with the overflow recess 18. On 85 the flat upper portion 20 of the basin may be provided a soap cup 21 having a depression 22 leading to the basin 10 in order that the cup 21 may be properly drained. Any suitable form of plug may be used in the 90 drain 19 and suitable pipes 23 and 24 are connected with each of the supply inlets 15 and 16. Each of the supply pipes 23 and 24 is provided with a valve of any suitable construction operated for instance as by push 95 buttons 25 as shown in Figs. 1 and 2. The back portion of the lavatory is provided 100 with a suitable number of pockets 26 by

means of which the lavatory may be secured to a wall 27 by means of bolts which may be litharged in said holes or sockets.

I claim:—

- 5 1. In a device of the class described, in combination, a lavatory basin and a sanitary fountain drinking cup, said lavatory basin and drinking cup being integrally formed and the cup having a recessed or bell shaped 10 mouth and located above the basin.
2. In a device of the class described, in combination, a lavatory basin and a sanitary fountain drinking cup, said drinking cup and basin being each formed of the same 15 material, and being each provided with a supply recess and a drain.
3. As an article of manufacture, a combined lavatory and sanitary drinking cup integrally formed, said lavatory having 20 formed also integrally therewith a supply spout, and said cup being provided with a drain.
4. As an article of manufacture, a combined lavatory and sanitary drinking cup integrally formed, said lavatory having 25 formed integrally therewith a supply spout, and being also provided with a drain and an overflow.
5. In a device of the class described, a 30 vitreous lavatory basin having a supply spout formed integrally therewith, and a sanitary fountain drinking cup, said basin, spout and cup being integrally formed.
6. In a device of the class described, in 35 combination, a vitreous lavatory and sanitary fountain drinking cup integrally formed, said drinking cup and basin each being provided with a source of supply.
7. As an article of manufacture, a vitreous 40 combined lavatory and sanitary fountain drinking cup, said drinking cup having formed therein a supply recess and said lav-

atory being provided also with an integrally formed spout.

8. As an article of manufacture, a combined lavatory and sanitary drinking cup, said lavatory and drinking cup being integrally formed and said cup being provided with a drain. 45

9. In a device of the class described, in combination, a lavatory and a sanitary fountain drinking cup formed of the same material, said lavatory being provided with an integrally formed spout, said sanitary cup being also provided with a supply recess and having also a drain. 50

10. As an article of manufacture, a combined vitreous flat back lavatory and a sanitary fountain drinking cup, said lavatory having an upwardly projecting back portion integrally formed therewith, said cup being formed on said upwardly projecting portion and formed integrally therewith, said lavatory and cup being each provided with a supply opening. 55

11. As an article of manufacture, a combined vitreous lavatory and sanitary drinking cup, said lavatory and drinking cup being each provided with a supply opening and said cup being also provided with a drain communicating with said supply openings. 60

12. As an article of manufacture, a combined lavatory and sanitary fountain drinking cup integrally formed, said lavatory and cup being each provided with a supply opening, said lavatory being provided also with a drain and an overflow outlet and said cup being also provided with a drain communicating with said supply openings. 70

JOHN H. GAVIN.
